UNITED STATES PATENT OFFICE.

OSCAR A. DE LONG, OF NEW YORK, AND ELEAZER KEMPSHALL, OF BROOKLYN, NEW YORK, ASSIGNEES, BY DIRECT AND MESNE ASSIGNMENTS, TO THE KEMPSHALL SPECIALTY MANUFACTURING COMPANY OF NEW JERSEY.

HOOK.

SPECIFICATION forming part of Letters Patent No. 511,326, dated December 26, 1893.

Application filed March 17, 1893. Serial No. 466,554. (No model.)

To all whom it may concern:

Be it known that we, OSCAR A. DE LONG, of New York, county and State of New York, and ELEAZER KEMPSHALL, of Brooklyn, county 5 of Kings, and State of New York, have invented certain new and useful Improvements in Hooks, of which the following is a full, clear, and exact specification.

Our invention relates to improvements in 10 hooks, particularly that class of hooks that are used in connection with eyes, the mechanical construction of which is hereinafter fully described.

The object of our invention is to construct 15 a sheet metal hook to be used in connection with a suitable eye, the mechanical arrangement of which hook being such that the accidental disengagement of the hook is almost impossible.

20 Another object is that this form of hook can be made much cheaper than the hook constructed of wire, inasmuch as it is formed of sheet metal which is cheaper than wire and which can be struck up by means of very simple machinery, very rapidly, into a hook fully as good as the wire hook.

Our invention is illustrated by the accompanying drawings, in which—

Figure 1 is a plan view of another form of 25 our invention. Fig. 2 is a vertical cross-section on the plane of the line 2—2 Fig. 3. Fig. 3 shows a plan view of a modification of our invention before the loop or hook is formed, and Fig. 4 is a side elevation of another modification of our invention.

35 A is a sheet metal blank from which the hook is formed. Suitable perforations B B may be formed in one end of the hook to secure it to the garment. To prevent the accidental disengagement of the hook from the eye, we cut two or more non-intersecting longitudinal slots in the shank and strike up the entire metal between the said slots to form a rigid raised bend between companion or adjacent slits. This raised portion is formed 45 preferably about midway between the bend forming the hook and the end by which the hook is attached to the garment. The spring

end E of the hook is preferably bent over and down sufficiently far so that the space that 50 intervenes between the said spring end E of the hook and the raised portion D, is so very slight that, for the ordinary eye to pass one way or the other through this narrow space without pressure sufficient to elevate the 55 spring end E of the hook, is impossible.

Fig. 3 illustrates a modification of a hook showing the preferable construction of a heavy hook to be used on heavy garments. In this case, if preferred, a blank may be struck out 60 of the center of the hook to lessen the weight of the hook, and one or more elevations D² may be struck up between companion slits for the purpose of preventing the accidental disengagement of the hook from the eye, as 65 before described.

Fig. 4 shows another modification in which the hump D³ is formed in the upper, or spring end E, of the hook instead of the lower side of the hook.

We are aware that a sheet metal hook having a raised portion, or a bent tongue, to prevent the disengagement of the hook has been used before, but in all instances one end of this bent tongue has been detached from the blank, 75 so that when the eye is passed into the hook the unattached end of the tongue is pushed down and is liable to wear into the garment to which the hook is attached. In this class of hooks having this bent tongue with one 80 end free, the tongue forms the spring. It is not so in our invention. The spring end E of our hook forms the spring in every instance. For, inasmuch as the elevated or raised portions D', D², D³, in our invention are all 85 formed as a solid part of, or attached at both ends to, the blank they can afford no spring whatever.

Having thus described our invention, what we claim, and desire to secure by Letters Patent, is—

1. A sheet metal hook consisting of the hook blank A said blank being provided with substantially parallel longitudinal slits, non-intersecting, the entire strip of metal between 95 companion slits being bent or struck upward

forming a rigid upward bend or bridge and with means at the rear of the hook as described for attachment, substantially as and for the purpose specified.

5. 2. A sheet metal hook consisting of a hook blank A the center of which is stamped out to form substantially parallel sides which meet at both ends of the hook blank, said sides being provided with rigid upward bends or bridges D² D² struck up from the entire

metal between two or more slits formed in the blank, and with means as described for attaching the hook to a garment, substantially as and for the purpose specified.

OSCAR A. DE LONG.
ELEAZER KEMPshall.
